UNITED STATES PATENT OFFICE.

ROBERT E. L. MILLER, OF FRONT ROYAL, VIRGINIA.

DENTAL CLAMP.

Application filed May 9, 1925. Serial No. 29,370.

To all whom it may concern:

Be it known that I, ROBERT E. L. MILLER, a citizen of the United States, residing at Front Royal, in the county of Warren and 5 State of Virginia, have invented certain new and useful Improvements in Dental Clamps, of which the following is a specification.

This invention relates to dental instruments, and especially to an improved form 10 of dental clamp.

In performing certain dental operations, especially the preparatory operations of taking impressions on wax as a guide for forming a set of lower teeth, it becomes 15 necessary to hold a wax mould on the lower gum from which the teeth have been extracted. In order that an arcuate piece of wax, extending from side to side of the mouth, and covering the lower gum, can be 20 securely held in place while the dentist performs the necessary operations in connection with said wax, I have provided a clamping device of such construction that it simultaneously engages opposite sides of such wax 25 mould, and engages the under side of the patient's chin, in clamping relation, thus securely holding the wax mould in place on the lower gum. In order that the device may be adjustable for engaging the opposite 30 sides of wax moulds of different sizes, the device is provided with pivots on which the mould-engaging elements are adjustably mounted, and it is also provided with means for securing the clamping elements in different clamping positions.

One object of the invention is to provide 35 a clamping device of this character which is of very simple construction, which is very convenient in application and operation, 40 and which is very effective for the purpose stated in the foregoing.

Other objects and important features are pointed out or implied in the following details of description, in connection with the 45 accompanying drawings, in which:

Figure 1 is a perspective view of the device in its effective position in connection with a patient's mouth having a wax mould therein. Fig. 2 is a perspective view of the 50 device shown separately. Fig. 3 is an enlarged sectional detail view, the section being in a vertical plane along the axis of the adjusting screw. Fig. 4 is an enlarged sectional view along the line 4-4 of Fig. 2.

55 Referring to these drawings in detail, in which similar reference characters corre-

spond with similar parts throughout the several views, and in which M indicates a patient's mouth having a wax mould W therein, said mould being provided with 60 lugs or lumps w, these being shown merely to assist in explaining the application of the device: The invention consists of a body or hub 5, a chin-engaging arm 6 provided with a bearing 7 journaled on the middle part of 65 the hub 5, a screw-socket 8 extending forward from the arm 6, a screw 9 which is preferably a thumb-screw in the screw-socket, a pair of reversed counterpart mould-engaging arms 10, and pivots 11 of these 70 counterpart arms. Each of these arms 10 is provided with one or more spurs 12, these spurs extending inward and inclined downward, that is, the spur or spurs 12 of each arm 10 extend toward the spur or spurs 12 75 of the other one of these arms, and their lower sharp ends constitute piercing elements for engaging with the lugs or lumps w, or with the penetrable sides of the wax mould independently of such lumps w. In 80 the present drawing, the lumps are shown exaggerated, for in practice, such lumps or seats are of very small size, and may be dispensed with, for the spurs can easily be pressed into the sides of the wax mould and thus form their own seats. When thus seated, either on the lumps or shoulders w, or in depression made by these spurs, their inwardly and downwardly pointing relation prevents them from becoming accidentally 85 disengaged from the wax mould.

Each arm 10 includes a substantially vertical lower portion and a substantially horizontal upper portion, these upper and lower portions merging with one another in substantially even curves at 10^a, thus enabling the arms 10 to extend rearward into the patient's mouth while avoiding pressure on the front part of the patient's chin.

95 The arm 6 has its free end provided with a substantially circular and upwardly convexed clamping element 13 which is adapted to comfortably fit against the under side of the patient's chin while pressing upward against the chin and thereby holding the arms 10 pressed down on the wax mould W.

100 Referring to Figure 3, it will be seen that the hub 5 has a cavity 14 whose wall includes a cam-surface 15 against which the inner end of the screw 9 operates for swinging the arm 6 upward with respect to the arms 10, 105 and for holding the arms 10 in clamping re-

lation with the arm 6. By means of this adjustment of the arm 6 about the hub 5, the clamping elements can very quickly be moved into and out of their clamping position; and at the same time, this adjustment is such that it is difficult to exert such clamping pressure that would cause pain or excessive uneasiness to the patient.

Both ends of the hub 5 are preferably 10 bifurcated, and the lower ends of the arms 10 are snugly fitted between the respective pairs of furcations, thus combining with the pivots 11 for rigidly securing the arms 10 against movement about the axis of the hub 15 when the latter is stationary. However, these arms 10 are freely and easily movable about their pivots 11 which are parallel with one another or have their axes lying in the same plane. They also have their axes in 20 the same plane as that of the intermediate part of the hub which serves as a journal for the circular opening or bearing 7, but it should be noted that the axis of this intermediate journal is at right angles to the axes 25 of the pivots 11.

It is evident that various changes of construction may be made without departure from the inventive ideas, and therefore, I do not intend to limit my patent protection 30 to the exact construction and arrangement of parts here illustrated.

What I claim as my invention is:

1. In a dental clamp, the combination of a body, two arms pivotally mounted at opposite ends of said body and provided with 35 means to engage with opposite sides of an article extending from side to side of a patient's mouth, the axes of the pivots of these arms being in the same plane, and a

third arm pivoted to said body substantially 40 between the pivots of said two arms, the axis of this third arm's pivot being substantially at right angles to the said axes of the other two pivots, this third arm being adapted to press against the under side of a patient's 45 chin in clamping relation to the other two arms, and means to hold these arms in their clamping relation.

2. In a dental clamp, the combination of a hub, two arms pivotally mounted at opposite ends of said hub, their pivots being substantially parallel, these arms being reversed counterparts of one another and having their free ends formed with elements 50 extending towards one another and adapted to engage with opposite sides of an article that extends from side to side of a patient's mouth, a third arm provided with a bearing 55 which extends around the part of said hub between the said two arms and is provided with means to press against the under side of the patient's chin in clamping relation to the other two arms, and means to hold these arms in their clamping relation.

3. The structure defined by claim 2, the 60 said elements on the counterpart arms constituting inclined spurs adapted to pierce 65 said article and thus prevent displacement of the counterpart arms with respect to said article.

4. The structure defined by claim 2, the 70 last said means including a cam-surface and a screw, said screw being operable against 75 said cam-surface for effecting different adjustments of said third arm with respect to said counterpart arms.

In testimony whereof I affix my signature.

ROBERT E. L. MILLER.
